(57) **CLAIM**

The ornamental design for a lipstick package, as shown and described.

DESCRIPTION

FIG. 1 is a perspective view of a lipstick package; FIG. 2 is a front view thereof, wherein the left side view, right side view, and back side view are each identical; FIG. 3 is a side view thereof, rotated 45 degrees along the vertical axis relative to the view of FIG. 2; FIG. 4 is a top view thereof; FIG. 5 is a bottom view thereof; and, FIG. 6 is perspective view thereof, shown with the cap removed to show aspects of the design that are not clearly visible when combined. In the drawings, the broken lines illustrate portions of the article which form no part of the claimed design.
